Primary Examiner — Patricia A Palasik

(57) **CLAIM**

The ornamental design for a video inspection robot as shown and described.

DESCRIPTION

1. Video inspection robot

2. Video inspection robot

1.1: Front

1.2: Back

1.3: Left

1.4: Right

1.5: Top

1.6: Bottom

1.7: Perspective

1.8: Perspective

2.1: Front

2.2: Back

2.3: Left

2.4: Right

2.5: Top

2.6: Bottom

2.7: Perspective

2.8: Perspective

Purpose of the design product: the video inspection robot is used for inspection, remote monitoring and scanning of on-shelf commodity information.

1 Claim, 16 Drawing Sheets
